ALARM LATCH

Logan W. Johnson, Minnetonka, Minn., assignor to Minnesota Mining and Manufacturing Company, St. Paul, Minn., a corporation of Delaware

Original design application Oct. 9, 1968, Ser. No. 13,905, now Patent No. 216,669. Divided and this application Nov. 25, 1969, Ser. No. 20,276

Term of patent 14 years

Int. Cl. D8—03

U.S. Cl. D8—131

FIG. 2

FIG. 3

FIG. 4

FIG. 5

FIG. 6

FIG. 1 is a front elevational view of an alarm latch embodying my design;

FIG. 2 is a bottom plan view of said alarm latch, the top view being substantially a mirror image thereof;

FIGS. 3 and 4 are side views of said alarm latch; and

FIGS. 5 and 6 are cross sectional views taken along the lines 5—5 and 6—6, respectively, of FIG. 1.

The back is free of ornamentation.

This is a division of design application Ser. No. D. 13,905, filed Oct. 9, 1968 and now patented No. D. 216,669.

I claim:

The ornamental design for an alarm latch, as shown and described.
